UNITED STATES PATENT OFFICE.

JAMES F. ATWOOD, OF BOSTON, MASSACHUSETTS.

CUFF-HOLDER.

SPECIFICATION forming part of Letters Patent No. 289,057, dated November 27, 1883.

Application filed October 8, 1883. (No model.)

To all whom it may concern:

Be it known that I, JAMES F. ATWOOD, of Boston, in the county of Suffolk and State of Massachusetts, have invented new and useful 5 Improvements in Cuff-Holders, of which the following is a specification.

In the accompanying drawings, in which similar letters of reference indicate like parts, Figure 1 is a view in perspective of a cuff-holder embodying my invention. Fig. 2 is a 10 side view of the same. Fig. 3 is a side view of the device in use, the sleeve and cuff being shown in section.

A flat piece of metal is bent into three folds— 15 viz., the fold A, serrated on the under or inner side, and preferably growing gradually thinner toward its outer end, the fold B, and the fold C, which is made thin, so as to form a spring, and is preferably but not necessarily 20 serrated on the surface next the fold A. A “safety-pin,” D, is secured by means of a perforation, d', in the shield d to an eye, E, rigidly secured to the bend between the folds A B. A tab, H, preferably of fabric, is secured by 25 a loop or wire, h, to the bend between the folds B C. Pivoted to the fold B is the bent cam-lever I, arranged to extend through a suitable opening in said fold and bear against the rear side of the spring C. The outer end 30 of the cam-lever is slightly turned up, in order that the thumb-nail may reach and move it.

The operation is as follows: The safety-pin D is secured to the lining K of the coat-sleeve

L. The cam-lever I is raised by placing the thumb-nail under the bent-up portion, and the 35 cam portion I' is drawn away from the spring C, (see broken lines, Fig. 2,) so that there is ample space between said spring and the fold A. The cuff P is slid into said space, as shown in Fig. 3, and the cam-lever I drawn 40 or pushed down into the position shown in Figs. 2 and 3, the cam portion I' forcing the spring C against the cuff, which is thus held tightly between the two serrated surfaces of the spring and fold A. By pulling slightly on 45 the tab H the device is firmly held while the cuff is being pushed into position.

Having thus fully described my invention, what I claim, and desire to secure by Letters Patent, is—

The herein-described improved cuff-holder, consisting, essentially, of the metallic piece formed into the three folds or layers A B C, the fold C extending between the folds A B by being bent inwardly, and made relatively 55 thin, the cam-lever I I', pivoted to the outer fold, B, and bearing against the inner fold, C, whereby the said fold C may be forced toward the fold A, and means for attaching the said metallic piece to the lining of a coat or the 60 shirt-sleeve, substantially as set forth.

JAMES F. ATWOOD.
